Primary Examiner — Dana K Weiland*Assistant Examiner* — Christina Gabrielle Cosden(74) *Attorney, Agent, or Firm* — Antoinette M. Tease**CLAIM**

The ornamental design for a hinge as shown and described.

DESCRIPTION

FIG. 1 is a front perspective view of a hinge showing the new design.

FIG. 2 is a rear perspective view of a hinge showing the new design.

FIG. 3 is a front view of a hinge showing the new design.

FIG. 4 is a rear view of a hinge showing the new design.

FIG. 5 is a top view of a hinge showing the new design.

FIG. 6 is a bottom view of a hinge showing the new design.

FIG. 7 is a left side view of a hinge showing the new design.

FIG. 8 is a right side view of a hinge showing the new design; and,

FIG. 9 is a perspective view of the hinge showing the new design in an alternate configuration with the environmental structure included.

The dashed broken lines in FIGS. 1-8 depict portions of the article that form no part of the claimed design. The dash dot broken lines shown in FIG. 9 depict environment that forms no part of the claimed design.
